UNITED STATES PATENT OFFICE.

ADOLPH STRIEMER, OF PHILADELPHIA, PENNSYLVANIA, ASSIGNOR TO CROMPTON & KNOWLES LOOM WORKS, OF WORCESTER, MASSACHUSETTS, A CORPORATION OF MASSACHUSETTS.

LOOM-STOPPING MECHANISM.

Application filed August 31, 1923. Serial No. 660,451.

To all whom it may concern:

Be it known that I, ADOLPH STRIEMER, a citizen of the United States, residing at Philadelphia, in the county of Philadelphia and State of Pennsylvania, have invented a new and useful Loom-Stopping Mechanism, of which the following is a specification.

This invention relates particularly to carpet looms of the Axminster type in which 10 yarn spools are supported on tube frames by which the yarn ends are presented between the warps of the fabric. In such looms it is desirable to provide means to stop the loom whenever a tube frame fails 15 to be properly advanced to delivery position.

It is the object of my invention to render the operation of such a stop motion more reliable, and to prevent irregular disabling of the stop motion mechanism at 20 times when its operation is required.

With this general object in view, my invention relates to certain arrangements and 25 combinations of parts which will be hereinafter described and more particularly pointed out in the appended claims.

A preferred form of the invention is shown in the drawings, in which

Fig. 1 is a partial side elevation showing 30 certain parts of a loom of the Axminster type;

Fig. 2 is a front elevation of the parts shown in Fig. 1;

Fig. 3 is a partial front elevation of a 35 tube frame and end support or bracket embodying my improvements;

Fig. 4 is a partial front elevation similar to Fig. 3 but partly in section and showing the parts in a different position;

Fig. 5 is a detail sectional plan view 40 taken along the line 5—5 in Fig. 3, and

Fig. 6 is a perspective view of a chain attaching hook.

Referring particularly to Figs. 1 and 2, 45 I have shown parts of an Axminster carpet loom including a loom side 10, one of a pair of positioning arms 11 by which a tube frame is detached from the transporting chain and is presented to the warps, a shipper lever 12 and loom stopping mechanism effective to release the shipper lever and controlled by one of the positioning arms 11.

The stopping mechanism comprises a bell

crank 13 mounted upon a fixed pivot 14 and 55 engaged by a cam plate or striker 15 at each revolution of the cam shaft 16. A rod 17 is pivoted at 18 to the upper end of the bell crank 13 and is provided with a hook or notch 19 normally positioned to engage a ledge 20 on an arm 21. The rod 17 has an extended end portion 22 which rests upon 60 the upper surface of the ledge 20, holding the hook or notch 19 normally in position to engage the ledge 20.

The arm 21 is mounted upon a short shaft 23 pivoted in the loom side 10 and provided at its outer end with a second arm 24 positioned to engage one arm 25 of a two-armed lever 26 which is pivoted upon a vertical 70 stud 27 supported by a bracket 28. The second arm 29 of the two-armed lever 26 engages a projection 30 on the side of the shipper lever 12 and when actuated by the stop motion moves the shipper lever to 75 throw off the power and stop the loom.

A vertical rod 31 is pivoted at 32 to the opposite end of the rod 17 and extends upward through a bearing 33 into position 80 for engagement by a portion of the positioning lever 11 as it moves downward by gravity to present the tube frame to the warp. When the rod 31 is thus engaged and pressed downward, it raises the hook 19 above the ledge 20, thus disabling the stop motion and preventing the operation thereof to stop the loom.

If each tube frame is not successively detached from the transporting chains, it is 90 required that the stop motion operate immediately to stop the loom. It has been found, however, that the positioning arms 11 sometimes slip off of a tube frame which is held in raised position and continue their downward gravity movement, thus disabling the stop motion at a time when its operation is desired.

An important object of my invention is 100 to provide means for preventing such irregular disabling of the stop motion mechanism. In Figs. 3, 4 and 5 I have shown a tube frame and supporting bracket which are of the general type shown in the prior patent to Ryon, No. 1,458,312 issued June 12, 1923.

These parts comprise a rectangular tubular member 40 (Fig. 4) having a spool bearing 41 and a chain engaging member or

guide 42 rigidly secured in the end thereof. An attaching hook 43 extends through a slot in the part 42 and is provided with a spring 44 within the tube frame which acts to press 5 the hook outward to engage the transporting chain. At a point closely adjacent to the pivotal point of support of the hook 43 I provide a lug or projection 45 (Fig. 6) for a purpose to be described.

10 The positioning arms 11 are provided at their outer ends with heads 11^a having side flanges 46 and a bottom flange 47 positioned to receive and support a tube frame. A stud or screw 48 threaded in each head 11^a 15 passes through an eye formed in the end of each arm 49. These studs 48 are provided for the purpose of engaging the hooks 43 and pushing them backward to the position shown in Figs. 3 and 4, thereby releasing 20 the tube frame from the transporting chain.

If, for any reason, the tube frame should fail to release from the transporting chains or should otherwise be prevented from moving downward, the downward gravity movement of the arms 11 will be prevented by engagement of the stud 48 with the lug 45 on the hook 43. This lug, being closely adjacent the pivotal point of the hook, has practically no motion and is always in 25 operative position. Such engagement of the stud with the lug or projection 45 will hold the arms 11 in raised position, so that an arm 11 cannot engage the rod 31 and disable the stop motion. The operation of the stopping 30 mechanism is thus rendered more certain and effective and irregular disabling thereof is prevented.

Having thus described my invention and the advantages thereof, I do not wish to be

limited to the details herein disclosed otherwise than as set forth in the claims, but what I claim is:—

1. In a loom having a plurality of yarn tube frames means to present said tube frames successively in yarn delivery position, 45 in combination, means to stop the loom when no tube frame is thus presented, a stop motion disabling device, a tube frame supporting arm actuated by gravity to move said device to disabling position, and means to prevent such movement of said supporting arm while the tube frame supported thereby remains in raised position.

2. A loom mechanism as set forth in claim 1, in which said latter means includes an attaching spring arm on each tube frame, in which said supporting arm has a releasing device movable to engage said spring arm and to disconnect the same and in which said latter means also includes a projection 60 in line with and normally below said releasing device and positioned for engagement thereby if said supporting arm slips downward relative to said tube frame.

3. A loom mechanism as set forth in claim 1 in which said latter means includes an attaching spring arm pivoted on each tube frame, in which said supporting arm has a releasing device movable to engage said spring arm and to disconnect the same, and 70 in which each spring arm has a projection adjacent its pivot normally below said releasing device and positioned for engagement thereby if said supporting arm slips downward relative to said tube frame.

In testimony whereof I have hereunto affixed my signature,

ADOLPH STRIEMER.
